PASQUALE GALASSI, OF NEW YORK, N. Y.

DIVIDING STRIP FOR TERRAZZO AND LIKE FLOORS

Application filed July 2, 1930. Serial No. 465,325.

This invention relates to dividing strips of the type used in the laying of terrazzo and similar floors, and more particularly refers to improvements in dividing strips comprising an upper uninterrupted longitudinal portion and longitudinally spaced lugs depending therefrom.

Terrazzo, granolithic, stucco and similar floors usually comprise a lower or foundation bed made of concrete or cement or mortar or other suitable material, and an upper or finishing layer generally consisting of a mixture of marble chips and cement, by means of which a good durable surface may be obtained as well as pleasing designs and color effects of a practically unlimited variety.

The upper layer which is generally placed in position after the foundation layer has been allowed to harden to a sufficient degree of consistency, is generally divided into a number of panels or units in a predetermined arrangement, which are obtained by outlining the desired design by means of 25 dividing strips placed on or through the foundation layer.

These strips generally consist of relatively thin and wide metal bars set on edge, said bars having their upper edges flush with the 30 surface of the floor, forming the desired design; said bars being generally provided with anchoring and positioning means insuring a firm binding action between the strips and the materials of which the floor is composed.

These bars are generally made of relatively soft metal such as brass for instance, the wearing qualities of which are approximately equal to those of the floor itself; and according to the nature of the floor and of the design to be produced, the dividing strips may be of various thicknesses and lengths.

Relatively thin strips may readily be obtained out of sheet metal, and are suitable 45 for floors of moderate size; however, relatively large floors, or floors composed of relatively large units, call for strips having sufficient rigidity to withstand the lateral pressure of the material without bulging 50 when the floor is laid.

These heavier strips are also generally made out of sheet metal but brass being an expensive material, their use materially increases the cost of the floor. At times the ornamental features are such as to require 55 extra thick metallic strips showing through the material, and in these cases, the cost is still higher.

In a copending application entitled, Floor strips, Ser. No. 375,052, I have described a 60 novel type of dividing strip, the lower portion of which is notched at spaced intervals so as to form a longitudinal series of lugs depending from the upper portion of the strip. Such a strip results in a material saving of 65 material as against an ordinary strip of the same thickness and width, and when made of light gauge material, sufficient rigidity may be imparted to the strip by forming its upper portion with a longitudinal rib member 70 close to the lower edge of said upper portion.

When the strip is made of relatively heavy gauge metal, the provision of a reinforcing rib is usually unnecessary, the material itself being sufficiently rigid to withstand 75 the lateral pressures imposed upon it.

On the other hand, when material of medium weight is used, the rigidity of the strip without the reinforcing rib member is frequently insufficient for all practical purposes; at the same time the provision of a longitudinal rib member obtained by embossing operations requires the use of very high pressures which in their turn call for 80 heavy and expensive presses and dies.

Even when the strip is made out of light gauge metal, it is necessary to use a relatively heavy press in order to produce the longitudinal rib member at one stroke, because these strips are generally six feet long, so that the cost of the equipment is at times so high that it can only be justified by a very large production or by a relatively high selling price.

The primary object of the present invention is to provide a strip of the type comprising an uninterrupted upper portion and a plurality of longitudinally spaced lugs depending therefrom, in which the reinforcing 100

feature is of a nature permitting the use of presses and machines lighter than those required by the strips to which my other above mentioned application refers.

5 Another object is to provide in a strip of the character specified, a type of reinforcement which may be used instead of the longitudinal rib member specified in my other application above referred to, adapted to 10 reinforce the weak sections of the strip without requiring the use of expensive presses, even when the strip is made out of relatively heavy gauge metal.

15 A further object is to provide in a dividing strip of the character specified, a novel and improved type of reinforcement adapted to impart to the strip the desired rigidity and at the same time to act as positioning and anchoring means for the strip.

20 Other objects and advantages of the present invention will more fully appear as the description proceeds and will be set forth and claimed in the appended claims.

25 Various embodiments of my invention are illustrated in the accompanying drawings, in which:—

Fig. 1 is a fragmentary side view in elevation of a strip having its lower portion notched at spaced intervals and provided 30 with reinforcing ribs in correspondence of its notched portions;

Fig. 2 is a cross sectional view of the same through line 2—2 of Fig. 1;

Fig. 3 is a fragmentary side view in elevation of a similar strip in which the reinforcing ribs are vertically displaced from the lower edge of the upper portion of the strip;

Fig. 4 is a cross sectional view of the same 40 through line 4—4 of Fig. 3;

Fig. 5 is a fragmentary side view in elevation of a strip of the same character illustrating a different type of reinforcing rib;

Fig. 6 is a cross sectional view of the same 45 through line 6—6 of Fig. 5;

Fig. 7 is a fragmentary side view in elevation of a similar strip in which the reinforcing ribs extend along the entire outline of the notches;

50 Fig. 8 is a cross sectional view of the same through line 8—8 of Fig. 7;

Fig. 9 is a fragmentary side view in elevation of a strip of a similar character in which the reinforcing rib extends all along 55 the outline of the notched lower edge of the strip;

Fig. 10 is a cross sectional view of the same through line 10—10 of Fig. 9;

Fig. 11 is a fragmentary side view in elevation of a strip having a plurality of longitudinally spaced dove-tailed notches along its lower portion, said strip being reinforced in accordance with my inventive idea;

Fig. 12 is a cross sectional view of the 65 same through line 12—12 of Fig. 11;

Fig. 13 is a fragmentary side view in elevation of a similar strip provided with a different type of reinforcing rib members;

Fig. 14 is a cross sectional view of the same through line 14—14 of Fig. 13;

Fig. 15 is a vertical cross section of a strip of the type shown in Figs. 11 and 12 in position; and

Fig. 16 is a vertical cross section showing a strip of the type shown in Figs. 5, 6 or 13, 14 in position, at the same time illustrating the function of positioning and anchoring means, performed by reinforcing rib members.

Referring to Figs. 1, 2, 20 designates a 80 floor strip comprising an upper portion 21 having an uninterrupted upper edge 22, and a plurality of spaced lugs 23 depending therefrom, said lugs having their lower edges 24 in alignment with one another and parallel to the upper edge 22.

85 Said lugs are preferably spaced at even intervals to form notches 25 which normally reach about midway of the width of the strip. The strip thus formed is preferably

provided with anchoring means which are represented by ears such as 26 struck off and 90

bent laterally of each lug, these ears becoming embedded in the floor material and preventing the strip from coming off after the 95 material has hardened. As illustrated in

the drawings, the floor strip is generally flat in form and the bottom edges of the 100 lugs have substantially the same thickness as the body portions of the lugs in accordance with the usual construction of terrazzo floor strips in order to facilitate setting the strip edgewise in the cementitious material

of the foundation bed of the floor.

105 A strip of the character described makes it possible to effect a considerable saving of material because two full width strips may be obtained out of a strip blank, the width of which is only equal to the height a of a single strip plus the height b of the upper portion of another strip, as explained in my

110 pending application above mentioned and in another copending application entitled Method of producing dividing strips for floors, Ser. No. 433,315. However, the section of the strip is considerably weakened in

115 correspondence of the notches and therefore it is necessary or desirable to so reinforce the strip that it will have sufficient rigidity to withstand the lateral pressure to

which it will be subjected while being laid. 120 In my other copending applications above referred to, this end is attained by providing a continuous longitudinal rib member at or near the base of the upper portion of the strip when needed. However, as stated it is at times difficult to produce such a continuous longitudinal rib especially when a material of relatively heavy gauge is used.

125 In view of the fact that the section of the

strip is actually weakened only in correspondence of its notches and not in correspondence of its lugs, I have therefore conceived the idea of providing reinforcing 5 rib members extending longitudinally above and slightly beyond the upper edge of each notch, thus reinforcing the strip only where a stiffening action is actually needed.

The reinforcements thus provided may 10 take various forms. For instance, in the form illustrated in Figs. 1 and 2, a rib or bead 27 is formed directly adjoining the edge 28 of each notch, said rib or bead extending slightly beyond each end of said 15 inner edge, as shown at 29, 30.

While it is preferable to provide a continuous longitudinal rib member when a light gauge metal is used, spaced rib or bead members 34, 35 directly above each 20 notch and slightly spaced from the inner edge thereof, said rib or bead members being alternately offset at one side and then at the other of the strip. Said strip furthermore illustrates the use of open top cup members such as 36, struck off and offset from the lugs, said cup members providing anchoring means which do not tend to weaken the section of the strip.

The strip illustrated in Figs. 5, 6, comprising a continuous longitudinal upper portion 36 and longitudinally spaced lugs 37 depending therefrom, forming notches 38, is reinforced by bending outwardly the inner edge of each notch forming flange members 39 extending laterally of the body of the strip. Said flange members provide an adequate reinforcement for the strip and at the same time act both as positioning and anchoring means for said strip, determining the depth at which the strip is to be inserted within the lower bed of the floor.

A similar type of reinforcement is shown in Figs. 7, 8, where the strip, comprising a continuous upper portion 40 and a plurality of longitudinally spaced lugs 41 depending therefrom, forming intervening notches 42, is reinforced by rib or flange members 43 which extend all around the outline of the notches.

A further modification of the type of rib or flange members shown in Figs. 5 to 8, illustrated in Figs. 5 to 8, is shown in Figs. 9, 10 where 44 designates the upper portion of the strip, 45 the lugs depending therefrom and 46 the notches intervening therebetween. In said strip, the entire lower edge including the sides of the notches and the lower edge of the lugs is bent outwardly to form a continuous flange 47 which acts to all intents and purposes as a continuous longitudinal rib, with the difference that all other conditions being equal less pressure is needed to bend the metal in order to produce the flange 47 than would

be required to produce an embossed longitudinal rib member.

Although in the case of Figs. 1 to 4, anchoring means independent of the reinforcing beads are provided and in the case of Figs. 5 to 10, the reinforcing means are also used as anchoring means, it is possible to dispense with the use of laterally offset elements for anchoring the strip in position if the notches are made with their sides spreading apart so as to form prong elements adapted to longitudinally extend into the plastic material of which the floor is composed.

A strip embodying this feature is shown in Figs. 11, 12 where 48 is the upper continuous portion of the strip and 49 are longitudinally spaced dovetailed lugs depending therefrom forming dovetailed notches 50 intervening therebetween. By virtue of this construction, the two ends of each lug are in the nature of pronged elements 51, 52 adapted to firmly anchor the strip in the floor composition, making it unnecessary to provide other anchoring means. The strip is reinforced in any one of the manners previously described, for instance, by providing ribs or beads such as 53 directly adjoining the base of each notch.

In Figs. 13, 14, I illustrate a similar strip comprising an upper portion 54 and a plurality of longitudinally spaced dovetailed lugs 55 depending therefrom, forming intervening dovetailed notches 56, in which the reinforcing and positioning means are obtained by bending outwardly the base of each notch forming flange members 57 similar to flange members 39 of the strip shown in Figs. 5, 6.

A strip of the type shown in Figs. 11 and 12 is shown in position in Fig. 15 where 58 designates the floor foundation, 59 the lower layer of the floor and 60 the upper layer. It will be observed that the reinforcing inner or base edges 53' of the notches are used as a means of determining the depth at which the strip is forced through the lower layer of the floor, so that the distance between said edges 53' and the upper edge of the strip determines the depth of the upper layer 60.

In Fig. 16, I illustrate the positioning and anchoring functions performed by the reinforcing flange or rib members 39 of a strip of the type shown in Figs. 5, 6, or of a strip of the type shown in Figs. 13, 14.

In said Fig. 16, 61 designates the floor foundation, 62 the lower layer of the floor, 63 the upper layer. It will be observed that rib or flange members 39 positively determine the depth at which the strip should be inserted within the lower layer and also provide reliable means for maintaining the vertical alignment of the strip.

Strips of numerous other designs could

- be illustrated all embodying my inventive idea which consists substantially in producing a strip of standard height, which permits of effecting a considerable saving 5 of metal as compared with the amount required by similar products heretofore known, said strip being reinforced wherever its section has been weakened by notching operations.
- 10 It is, of course, also within the scope of my invention to apply the method of reinforcing above described, in connection with strips having portions reaching down to their lower edge struck-off and bent laterally of the strip for the purpose of producing 15 positioning and anchoring means therefor, such as shown for instance in Patent No. 1,371,857.
- In a similar manner, my invention can 20 also be applied in connection with those strips which, although, having both their upper and their lower edges uninterrupted, have their section weakened at points where openings are formed by blanking operations 25 or by striking off and laterally bending portions of the body of the strip for the purpose of forming anchoring means therefor.
- The drawings are intended for illustrative purposes only and not in a limiting 30 sense; I therefore reserve the right to carry my invention into practice in all those ways and manners which may enter, fairly, into the scope of the appended claims.
- I claim:
- 35 1. A floor pattern and guide strip comprising a metallic strip having an upper portion provided with an uninterrupted edge, a lower portion comprising spaced lugs and intervening notches, the bottom edges of 40 said lugs having substantially the same thickness as the body portions thereof, and spaced laterally projecting rib-members in said upper portion spaced from the top of said notches.
- 45 2. A floor pattern and guide strip comprising a metallic strip having an upper portion provided with an uninterrupted edge, a lower portion comprising spaced lugs and intervening notches, the bottom 50 edges of said lugs having substantially the same thickness as the body portions thereof, and spaced rib members projecting from opposite sides of said upper portion adjacent the lower edge thereof and positioned over 55 the notches between said lugs.
3. A pattern and guide strip for floors having a foundation layer of plastic material and an upper layer of plastic material, comprising a metallic strip having an upper 60 portion having an uninterrupted upper edge adapted to be exposed at and flush with the top surface of the upper layer of the floor, a lower portion comprising a plurality of spaced lugs and intervening notches, said 65 lugs adapted to be embedded in the founda- 70 tion layer of the floor, the bottom edges of said lugs having substantially the same thickness as the body portions thereof, and laterally projecting spaced ribs at the top of said notches adapted to be positioned at the top of the foundation layer of the floor thereby to constitute positioning means for the strip to determine the depth of said upper layer of plastic material.
4. A pattern and guide strip for floors 75 having a foundation layer of plastic material, comprising a metallic strip having an upper portion having an uninterrupted upper edge adapted to be exposed at and flush with the top surface of the upper layer of the floor, a lower portion comprising a plurality of spaced lugs and intervening notches, said 80 lugs adapted to be embedded in the foundation layer of the floor, the bottom edges of said lugs having substantially the same thickness as the body portions thereof, and spaced ribs projecting laterally from opposite sides of said upper portion and positioned at the lower edge thereof over said 85 notches, adapted to be positioned at the top of the foundation layer of the floor thereby to constitute positioning means for the strip to determine the depth of said upper layer of plastic material.
